UNITED STATES PATENT OFFICE

2,479,173

CIRCUIT AND STARTER FOR ELECTRIC
DISCHARGE DEVICESEugene Lemmers, Cleveland Heights, Ohio, as-
signor to General Electric Company, a corpo-
ration of New York

Application July 26, 1944, Serial No. 546,621

1 Claim. (CL 315—99)

1

This invention relates to the starting control of electric discharge devices, and is very useful for fluorescent tubes of positive column discharge type, as well as for various other discharge devices. The invention is especially adaptable for starting discharge devices quickly, without the delay usually entailed by preheating their cathodes. It lends itself with peculiar advantage to the conversion of "hot-starting" or "cathode-preheating" systems to virtually instantaneous "cold starting," without cathode preheat.

As is well known, the voltage required to start a discharge through gas or vapor is considerably higher than that required to maintain it after it has started. Even this operating voltage is often different from ordinary lighting supply circuit voltages. Accordingly, a transformer is generally interposed between the supply circuit and the discharge circuits of an installation, to give the required voltage. In any case, current-limiting chokes or ballasts (usually having inductance) are commonly included in the discharge circuits.

Most fluorescent lamps of positive column low pressure discharge type are at present "hot-starting," with flow of heating current through their cathodes to preheat them before discharge is initiated. For this purpose, a starting circuit with an automatic switch therein is connected across the discharge circuit, in parallel with the discharge gap of the lamp and through heating means embodied in the cathodes. The automatic switch passes current through the cathode-heating means long enough to bring the cathode(s) of a lamp up to an adequate emissive temperature, and then suddenly opens the starting circuit, giving rise to a high voltage "kick" between the electrodes (due to the inductance in the discharge circuit, and much higher than the operating voltage of that circuit) which generally suffices to initiate the discharge.

The time required to preheat the cathodes to the operating temperature of adequate thermionic emission is appreciable, so that at best an undesirable brief interval elapses between the closing of the wall switch or other manual switch controlling an installation and the actual lighting up of the lamps. Moreover, the action of starters in common use is often irregular, so that the lapse of time between closing the control switch and lighting up all the lamps may often amount to a quarter of a minute, more or less. These drawbacks have heretofore been unavoidable in practice, because starting of lamps "cold," without cathode preheat, resulted in rapid distintegration of the cathodes and blackening of the lamps.

2

Recently, cathodes have been evolved which stand cold starting so much better that it would seem feasible to do away with hot starting and with starting switches, so that fluorescent lamps would light instantly (or practically so) when the controlling switch is closed, just like incandescent lamps. For this purpose, a leakage-reactance transformer interposed between the lighting supply circuit and the discharge circuits may be provided, to give high open-circuit voltage for initiating discharge, followed by suitably lower voltage for ordinary operation.

While this arrangement is generally successful and satisfactory, it has the disadvantage of requiring larger and more expensive transformers than those now in use for hot-starting installations. Moreover, it makes the advantages of quick cold-starting unavailable to present users of fluorescent lamps without expensive alterations of their installations, requiring new auxiliaries which under existing circumstances may not be available for some time to come.

To meet the problems thus presented, I have devised starting systems or arrangements which afford quick or virtually instantaneous starting combined with the advantage of utilizing present inexpensive types of equipment and systems of wiring unaltered, whether for new installations or in existing installations. This I accomplish with novel switch arrangements actuated on the piezo-electric principle, and virtually instantaneous in their action, or practically so. Such a switch can be adapted to most or all of the known starting systems; and in the case of existing hot-starting installations, it can be substituted for present delayed action starters with no more trouble than is involved in replacing the present starters when worn out. While piezo-electric operation is especially suited for operation of discharge devices on A. C., it can also be adapted to devices operated on D. C. by including in series with it a "buzzer" or other means for producing suitably rapid intermittent current and voltage impulses.

Various other features and advantages of the invention will appear from the description of species and forms of embodiment, and from the drawings.

In the drawings, Figs. 1, 2, 3, and 4 are diagrams illustrating the application of my piezo-electric switches to various types of discharge lamp circuit.

Figs. 1 and 2 illustrate the application of the invention to a discharge device 1 such as the low pressure positive column fluorescent lamp exem-

plified in U. S. Patents Nos. 2,294,203 to Peters, 2,330,161 to Townsend, and 2,306,925 to Aicher, heretofore ordinarily started "hot" after a period of cathode preheat. As shown in Fig. 1, the tubular radiation-transmitting envelope of the device 1 has spaced-apart activated thermionic cathodes 2, 2 in its ends. These electrodes 2, 2 may be of the usual coiled or coiled-coil tungsten filament type, coated or charged with activating oxides such as a mixture including barium and strontium oxides. The envelope may contain a low-pressure atmosphere of starting gas, such as argon at a pressure of 2 to 4 mm. of mercury, or other inert rare gas(es) at a corresponding pressure, and also a vaporizable and ionizable working substance or metal such as mercury, of which a surplus supply (exceeding what will vaporize during operation of the device) is indicated by a mercury droplet 3 inside the envelope. An internal coating of fluorescent material or phosphor 4 on the envelope walls is also indicated.

The discharge device is shown connected across a discharge circuit 5 including the inductive ballast 6, which also serves as a starting inductance, and the make-and-break wall or other manual switch 7. For energizing it, the discharge circuit 5 is shown connected across the secondary of an autotransformer 8 whose primary connection is across a voltage source such as an ordinary 60 cycle A. C. lighting circuit of some 110 to 120 volts, for example. To illustrate usual conditions of operation, two similar discharge devices 1, 1 are shown connected across the transformer secondary in parallel lead and lag circuits 5, 5, one of which includes a condenser 9. The transformer 8 is of course chosen to give or assure the desired voltage across each of the discharge circuits 5, 5, which for an ordinary 40 watt fluorescent lamp may be of the order of 220 volts R. M. S. on open circuit, more or less. Once the discharge has started, the voltage across each device 1 is regulated or reduced by its ballast 6 to a favorable value for the operation of the device 1, which may be the closed circuit voltage on which the device would be operated in present hot-starting practice.

For the purposes of my invention, a starting circuit 10 is shown connected across the discharge circuit 5 (or across each of the circuits 5, 5) through or at the cathodes 2, 2 of the corresponding discharge device 1, as is usual in present hot-starting practice; and in this starting circuit is interposed an interrupting switch 11 that is piezo-electrically operated or actuated, by means of any suitable crystal member 12, such as piezo-electric Rochelle salt, for example. As shown, the crystal member 12 is connected in the starting circuit 10 (and thus across the discharge circuit 5) very much like a condenser, in shunt with the switch 11. In the case of the lamp 1 in the lag circuit 5, a condenser 13, suitably of about 1 mfd. capacity for a 40-watt lamp 1, may be connected in circuit 10 in series with the switch 11. The crystal member 12 may consist of one single crystal with metallic foil affixed and electrically connected to its opposite faces and to the lead wires of the starting circuit 10; or it may consist of two superposed crystals with foil cemented between their adjacent faces and other foils affixed to their opposite, remote faces, one lead wire being then connected to the intermediate foil, and the other to both the outer foils. A rectangular crystal member 12 may be supported at one end and may carry a motion-multiplying arm 14 attached to its other end, with

the free arm end 15 in position to engage a movable resilient contact 16 of switch 11 and push it away from a fixed contact of this switch, and vice-versa. With the particular arrangement shown, the switch 11 may be open when the circuits 5, 10 are unenergized, since at that time the crystal member 12 is not deformed or bent either way. When A. C. voltage impulses are applied to the crystal member 12 as a result of energization of the circuits 5, 10, the crystal member 12 twists or flexes in opposite directions alternately.

A mode of operation of the system shown in Fig. 1 is that when the switch 7 is closed to turn on the lamps 1, 1, A. C. voltage is applied in each starting circuit 10, as well as in the corresponding discharge circuit 5, and a weak A. C. current (of the order of some 15 microamperes, more or less) traverses the crystal member 12. On the first voltage impulse in the proper direction, the crystal member 12 flexes or twists to the right in Fig. 1, the switch 11 automatically closes, and a heavier current flows in the circuit 10 via the switch 11. On the ensuing reverse voltage impulse, the crystal member 12 flexes or twists to the left in Fig. 1, and thus allows or compels the switch 11 to open. This action may be repeated during several A. C. voltage cycles in the discharge circuit 5, until on one of the opening movements of switch contact 16 the resulting voltage kick between the electrodes 2, 2 is in such phase relation to the discharge circuit voltage between these electrodes and of such magnitude that the discharge starts. The action is so rapid, however, that to the eye, and for practical purposes, the lamp 1 starts instantaneously when the switch 7 is closed. Once started, the discharge shorts the starting circuit 10, including both the switch 11 and the crystal 12, so that further operation of the switch 11 during the running of the lamp 1 does not occur, or has no material effect.

The effect of the capacitor 13 in the circuit 10 of the lag-circuit lamp 1 is to improve the starting action, making it possible to start on lower voltages in the lag discharge circuit 5, and with fewer operations of the switch 11 for each start. For example, with a condenser 13 of 1 mfd. capacity, a 40-watt fluorescent lamp will start virtually instantaneously on a voltage of 180 volts in the circuit 5. While this action of the condenser 13 to assist starting is somewhat obscure, and is not of course dependent on the correctness of any theory, there is reason to believe that after each opening of the switch 11 the condenser 13 is left charged by the resulting high voltage kick, and that since at the next closing of the switch 11 the voltage in circuits 5, 10 has reversed, the condenser potential then adds to the supply potential in the circuits 5, 10 as the energy stored in the condenser is "dumped" through the lamp 1. Studies of the starting action show that if a condenser 13 of 1 mfd. capacity is charged to about 900 to 1000 volts D. C., a discharge in lamp 1 starts on a single make by switch 11; while if this same condenser 13 is charged to only about 170 volts D. C., some six successive make and break cycles by switch 11 (each with the condenser so charged) must occur before the discharge starts.

The capacity of the condenser 13 is not very critical: e. g., a 40-watt fluorescent lamp starts as well with a 3 or 4 mfd. condenser as with a 1 mfd. condenser, or somewhat better; and, on the other hand, a condenser of less than 1 mfd. is also more or less helpful. A condenser of such

small capacity as $\frac{1}{4}$ mfd. requires some 20 makes-and-breaks for a start if charged each time to about 170 volts.

The system shown in Fig. 2 differs from that in Fig. 1 in that the movable contact 16 of switch 11 is carried by the crystal 12 or its motion-multiplying arm 14, instead of being resiliently flexed by the arm, and in having a glow-discharge device or glow-lamp 17 connected in series with the crystal member 12 across the switch 11. Before the discharge in lamp 1 starts, the full open-circuit voltage in the lag circuit 5 is applied across the glow device 17 and suffices to break it down and maintain a discharge through it, so that A. C. voltage is applied to crystal member 12, and switch 11 operates as above described. While lamp 1 is in operation, however, the voltage across circuit 10 is so reduced that glow device 17 ceases to pass current and "drops out," thus opening circuit 10 so that A. C. voltage is no longer applied to crystal member 12, current flow through it ceases, and switch 11 does not operate.

Figs. 3 and 4 illustrate the application of the invention to a discharge device 1 such as a cold-starting low pressure positive column fluorescent lamp, exemplified in U. S. Patents Nos. 2,146,579 to Inman and 2,306,925 to Aicher. The system shown in Fig. 3 differs from that in Fig. 1 in that the starting circuit 10 with its switch 11 and crystal member 12 is connected directly across discharge circuit 5 between ballast 6 and discharge lamp 1, instead of through the cathode coils 2, 2; or, in other words, circuit 10 is connected across the cathodes 2, 2 partly through the discharge circuit leads. As shown in Fig. 3, a capacitor or condenser 19 of moderate capacity is interposed in circuit 5 between ballast 6 and circuit 10.

In the system shown in Fig. 4, the starting circuit 10 is connected across discharge circuit 5 in advance of ballast 6, but includes a coil 20

in inductive relation to ballast 6, or, in other words, the secondary of a transformer or induction coil having the coil of ballast 6 as its primary. A resistance 21 is shown connected in circuit 10 in series with switch 11, crystal member 12, and coil 20, for regulating and controlling the voltage and current in circuit 10.

In Figs. 2, 3, and 4, various parts and features are marked with the same reference characters as their homologues in preceding figures, in order to dispense with repetitive description.

What I claim as new and desire to secure by Letters Patent of the United States is:

In combination with a gaseous electric discharge device having a starting circuit in parallel therewith and an inductive member in series therewith operable upon making and breaking of the starting circuit to induce a relatively high voltage across the device for starting it, a starting switch having its contacts connected in said starting circuit to make and break the circuit, and a piezo-electric crystal electrically connected in said starting circuit to be distorted upon application of potential thereto and physically arranged to actuate said switch contacts upon distortion thereof, and a capacitor in series with said switch.
